PITCH RAISING DEVICE

William Tolman Weedin, Tulsa, Okla.

Application September 18, 1939, Serial No. 295,490

4 Claims. (Cl. 84—312)

This invention relates to an attachment for guitars and the like stringed instruments, whereby the pitch of any desired string or strings of the instrument may be instantly raised while playing the instrument so that additional chords may be struck without changing the tuning of the instrument by operation of the usual tuning pegs or keys.

An object of the present invention is to provide a device of the above kind which is comparatively simple in construction, efficient in use, and easily applied to the instrument.

Another object of the present invention is to provide a device of the above kind wherein a pitch changing device is provided for each string of the instrument, and wherein each pitch changing device may be adjusted so as to be operable for varying the pitch of the associated string any desired amount and to effect an accurate change of pitch.

With the above general objects in view, and others that will become apparent as the nature of the invention is better understood, the present invention consists of the novel form, combination and arrangement of parts hereinafter more fully described, shown in the accompanying drawing and claimed.

In the drawing:

Figure 1 is a side view showing a portion of the neck and neck head of a guitar, and illustrating the device of the present invention in position upon the neck head of the instrument,

Figure 2 is a face or top plain view of the device shown in Figure 1,

Figure 3 is a fragmentary longitudinal sectional view thereof drawn on an enlarged scale, and

Figure 4 is a perspective view of one of the presser bars forming part of the present invention.

Referring in detail to the drawing, 5 indicates the neck and 6 the neck head of a guitar or like musical instrument having strings 6a tensioned over a nut 7 and tuned by operation of the usual tuning keys 8 carried by the neck head 6. The usual fret bars 9 are provided across the neck 5 under the strings 6a.

The present attachment includes a base plate 10 fastened by means of screws 11 or the like upon the neck head 6 between the nut 7 and the keys 8, said base plate 10 carrying a plurality of pitch changing devices 12, one for each of the strings 6a.

Each pitch changing device 12 consists of a U-shaped sheet metal bracket having its intermediate portion fastened upon the base plate 10 by

riveting or the like as at 13, the side members of the bracket being parallel with the associated strings 6a which passes therebetween. Pivoted mounted on and between the side members of each bracket is a presser bar 14 whose pivot 15 is provided at one end thereof so that the presser bar is mounted for vertical swinging movement. Suitable springs 16 are provided between the side members of the bracket and between the intermediate portion of the bracket and the associated presser bar 14 for normally yieldingly elevating the latter out of contact with the associated string. Means is associated with each presser bar for forcing the same downwardly in to contact with the associated string 6a for changing the pitch thereof, and such means consists of an internally threaded tube 17 pivoted at its lower end as at 18 for rocking movement and having a screw 19 threaded therethrough. The lower end of the screw 19 projects at the bottom of the threaded tube 17 for engagement with the associated presser bar 14 when the tube 17 is swung upwardly to the full line position of Figure 3. When this is done, the associated presser bar 14 is forced downwardly so as to exert a downward pressure upon the adjacent string 6a to thereby change the pitch of the latter. At this time, the flat lower end of screw 19 flatly contacts the upper surface of the associated presser bar 14 so as to maintain the latter in engagement with the string, the tension of the springs 16 holding the presser bar 14 in contact with the lower end of screw 19 so that the parts are maintained in this pitch changing position until manually operated.

By simply swinging the screw 19 and tube 17 downwardly to the dotted line position of Figure 3, the presser bar 14 is released so that it is swung upwardly by the spring 16 out of engagement with the adjacent string 6a of the instrument for permitting said string to return to its normal pitch. By adjusting screw 19 longitudinally through the tube 17, the desired change of pitch may be varied and accurately adjusted. A jam nut 20 is threaded on the screw 19 in position to jamb against the upper end of the tube 17 for securing the screw 19 in its adjusted position. By providing a pitch changing device of this kind for each string and mounting all of the pitch changing devices upon a common supporting base, a unitary structure is had which may be readily applied to the instrument. Each pitch changing device is independently operable so that the pitch of each string may be independently changed and so that any desired one or more

of the strings may be easily changed in pitch. With an ordinary guitar, the user is able, by means of the present attachment, to obtain the same number of chords as are possible in a double neck guitar, without operating the tuning keys to change the entire tuning of the instrument. By making the presser bars 14 flexible, they may yield to the pressure of the screws 19 when the latter are adjusted to obtain a change in pitch greater than a semi-tone.

It will be apparent that each pitch changing device is identical with the rest so that specific description of one will suffice for all. In the instrument shown, there are six strings, and a pitch changing device is provided for each of these strings. The present invention makes it possible to obtain added chords quickly while playing the instrument, and it is not necessary to manually hold the parts 17 and 19 in the pitch changing position or in the position wherein the presser bars are released from the strings.

What I claim as new is:

1. In a pitch changing means of the character described, a pitch changing device comprising a U-shaped bracket, a presser bar pivoted at one end between the sides of said brackets and under which the string of the instrument is adapted to pass, a pivoted element mounted between the sides of the bracket and movable to a set position to depress and maintain the presser bar into engagement with the string or to another position wherein the same is disengaged from said presser bar, and a spring for elevating said presser bar out of engagement with the string when the pivoted element is disengaged from said presser bar.

2. In a pitch changing means of the character described, a pitch changing device comprising a U-shaped bracket, a presser bar pivoted at one end between the sides of said brackets and under which the string of the instrument is adapted to pass, a pivoted element mounted between the sides of the bracket and movable to depress the presser bar into engagement with the string or to another position wherein the same is disen-

gaged from said presser bar, and a spring for elevating said presser bar out of engagement with the string when the pivoted element is disengaged from said presser bar, said element including a member having a flat end engageable with the presser bar whereby the element is maintained in the presser bar depressing position when set in such position.

3. In a pitch changing means of the character described, a pitch changing device comprising a U-shaped bracket, a presser bar pivoted at one end between the sides of said brackets and under which the string of the instrument is adapted to pass, a pivoted element mounted between the sides of the bracket and movable to a set position to depress and maintain the presser bar into engagement with the string or to another position wherein the same is disengaged from said presser bar, and a spring for elevating said presser bar out of engagement with the string when the pivoted element is disengaged from said presser bar, said element comprising a pivoted internally threaded tube, and a screw adjustably threaded through said tube and arranged to have its lower end impinge the presser bar.

4. In a pitch changing means of the character described, a pitch changing device comprising a U-shaped bracket, a presser bar pivoted at one end between the sides of said brackets and under which the string of the instrument is adapted to pass, a pivoted element mounted between the sides of the bracket and movable to a set position to depress and maintain the presser bar into engagement with the string or to another position wherein the same is disengaged from said presser bar, a spring for elevating said presser bar out of engagement with the string when the pivoted element is disengaged from said presser bar, said element comprising a pivoted internally threaded tube, and a screw adjustably threaded through said tube and arranged to have its lower end impinge the presser bar, said presser bar comprising an elongated strip of resilient material.

WILLIAM TOLMAN WEEDIN.
